SOUND AMPLIFIER

Filed Feb. 19, 1930

Inventor
CHARLES McLEAN

By *Livingston McCallum* *Attorney*

UNITED STATES PATENT OFFICE

CHARLES MCLEAN, OF MARICOPA, CALIFORNIA

SOUND AMPLIFIER

Application filed February 19, 1930. Serial No. 429,723.

This invention appertains to radio broadcasting and receiving sets and more particularly to novel means for amplifying the sound waves without distortion thereof so as to 5 materially increase the volume of said waves.

One of the primary objects of my invention is the provision of means for amplifying the sound waves by the provision of the use of a sealed air-tight container or bell having 10 air under pressure therein with a microphone and a loud speaker at the respective ends thereof so that the sound waves are made to pass through the compressed air, it being found that the passage of the waves through 15 the compressed air will materially amplify the same.

Another important object of my invention is the provision of an improved loud speaker embodying a sealed container or bell having 20 air under pressure therein with a receiver or speaker connected with the radio receiving set placed in the sealed container or bell at one end thereof and a microphone or transmitter arranged at the opposite end of the container 25 or bell for receiving the sound waves from the receiver or speaker, the transmitter or microphone being in turn connected with a loud speaker arranged exteriorly of the bell, whereby the amplified sound waves can be 30 thrown into the atmosphere.

A further object of my invention is the provision of a novel collecting port arranged in the sealed container or bell for receiving the microphone, the collector or shield acting 35 as means for guiding the sound waves transmitted to the compressed air in the sealed container or bell against the diaphragm of the microphone.

A still further object of my invention is to provide an improved amplifying device of the above character, which will be durable and efficient in use, one that will be simple and easy to manufacture and one which can 45 be placed upon the market at a reasonable cost.

With these and other objects in view, the invention consists in the novel construction, arrangement, and formation of parts, as will 50 be hereinafter more specifically described,

claimed, and illustrated in the accompanying drawing, in which drawing:

The figure is a diagrammatic showing of my improved loud speaker showing the same in longitudinal section. 55

Referring to the drawing in detail, the letter A generally indicates my improved loud speaker which comprises a sealed container or bell B preferably formed of metal of the desired gage and of sufficient strength to 60 hold the air under pressure therein, said air being forced in the bell B through a suitable air supply valve 5 from any source of supply. The bell should likewise be provided with an air pressure gage 6 of any standard 65 construction.

As shown, the sealed container or bell B is of a substantially conical body 7 having an arcuate end wall 8.

The narrow or apex end of the body 7 is 70 provided with a neck 9 while the arcuate end wall 8 in alignment with said neck 9 is provided with a neck 10.

The improved device A is adapted to be interposed between the usual radio receiving set (not shown) and any preferred type of loud speaker and in accordance with my invention I place a receiver or speaker 15 within the sealed container or bell B adjacent to the narrow or converged end thereof and the usual loud speaker wires 16 for the radio receiving set (not shown) is led through the neck 9 into the bell and connected with said receiver or speaker. A cement or other filler 16 can be placed in the neck 9 85 around the wires 16. 80

At the opposite end of the bell and interiorly of the same and in longitudinal alignment with the receiver or speaker 15, I 90 place a microphone 18, which is in turn connected with a loud speaker or receiver 19 arranged exteriorly of the bell by suitable connection 20 which extends through the neck 10. A suitable cement 21 is placed in the neck around the connection 20. 95

If desired, a collector shield can be placed around the microphone 10, the same being indicated by the reference character 22, so as to direct the waves against the diaphragm of the microphone. 100

By the use of compressed air in the container, I have found that the sound waves are amplified and thus the volume of the receiving set is greatly increased by the use ⁵ of my device.

Changes in details may be made without departing from the spirit or the scope of this invention, but:—

What I claim as new is:

- 10 1. In a device of the class described, a sealed container having air under pressure therein, a speaker arranged in said container at one end thereof, a microphone in said container at the opposite end thereof, and
- 15 an exteriorly arranged loud speaker mounted upon said container and operatively connected with the microphone.
- 20 2. In a device of the class described, a sealed container having air under pressure therein, including an elongated conical body and an arcuate end wall connected with the large end of the conical body, a speaker arranged in the narrow end of the conical portion of the body facing toward the arcuate end wall, a microphone arranged in the container facing the speaker and adjacent to the arcuate end wall, and a loud speaker mounted upon and arranged exteriorly of the container and operatively connected to ²⁵ the microphone.
- 30

In testimony whereof I affix my signature.
CHARLES MCLEAN.
